MECHANISM FOR GRINDING

Merton H. Arms, Springfield, Vt., assignor to
 Bryant Chucking Grinder Company, Springfield, Vt., a corporation of Vermont

Application August 13, 1940, Serial No. 352,380

12 Claims. (Cl. 51—100)

This invention relates to the grinding of work and is particularly concerned with internal grinding.

One of the features of the invention relates to a multiple selective control of the feed of a grinding wheel spindle whereby the feed of the grinding wheel may be controlled selectively in accordance with a plurality of definite laws of action at different times, and if desired for operation on different portions of a piece of work.

One specific example of the use of such a control is found in grinding the bores of internal combustion engine cylinders particularly where the engine head is made of a relatively light weight alloy and has a threaded connection with the barrel portion. In such work a very small departure from accurate cylindricity has been found desirable, particularly adjacent to the barrel ends. Such departures may also be found desirable at other portions. In accordance with this invention as applied to this type of work, the rough grinding may be cylindrical, the final grinding, only, providing for such departures from cylindricity.

An object of the present invention, therefore, is to provide a method and mechanism for effecting such multiple feed control in a selective manner.

For a more complete understanding of this invention, reference may be had to the accompanying drawings in which

Figure 1 is a front elevation of a grinding machine embodying the invention as applied to the grinding of engine cylinder bores.

Figure 2 is a diagrammatic sectional view on line 2—2 of Figure 1, the departure from cylindrical of the work and the wheel being greatly exaggerated.

Figure 3 is a view partly in side elevation and partly broken away and in section of an engine cylinder showing the contour of the bore, the variation from cylindrical being exaggerated for clarity of showing.

Figure 4 is a detail section on line 4—4 of Figure 1.

Figure 5 is a view similar to a portion of Figure 4, but showing a modification.

Figures 6, 7 and 8 are somewhat diagrammatic views illustrating the work, grinding wheel and certain of the control mechanism in various relative positions.

Figures 9 and 10 are views similar to Figures 7 and 8, respectively, but showing a modified construction and arrangement.

Figure 11 is a fragmentary longitudinal section

showing much exaggerated the cylinder wall contour produced by the mechanism of Figures 9 and 10.

Figures 1 and 4 illustrate an internal grinding machine of the well known Bryant type and as shown generally in the Arms Patent No. 2,176,985. It comprises a base 1, a rotary work support 2 and a rockable and axially movable wheel carrier 3. This wheel carrier is mounted for its rocking motion on an overhead axis of a cylindrical control bar 4 and the lower end of this carrier is provided with an extension 5 which rests by gravity against a suitable feed control mechanism along which this extension rides during the axial traversing motion of the carrier 3. This carrier 3 supports a grinding wheel spindle 6 carrying a grinding wheel 7 at one end and a driving pulley 8 at the other. A driving belt 9 passes around the pulley 8 and about suitable idlers 10 and 11, and about a drive pulley 12 of a motor 13.

As shown best in Figures 4 and 5, the extension 5 carries a pair of abutment members 20 and 21 at different radial distances from the axis of the control bar 4, either of which may be employed as desired. The abutment member 20 is shown as a bar of circular cross section clamped in position by means of a clamping jaw 22 which may be secured in position as by bolts, one of which is shown as at 23. The abutment 21 is shown as a flat bar secured in adjusted position by screws such as 24 and adjustable substantially horizontally as by adjusting screws 25 provided with lock nuts 26. Both the abutments 20 and 21 extend for a substantial distance generally parallel to the member 4 so that they control the angular position of the wheel support 3 during the traverse of the grinding wheel along the interior of the work. Cooperating with the abutment 20 is a feed bar 30 which may carry a cam roller 31 at its rear end abutting the abutment 20. Similarly the abutment 21 may be engaged by a follower 32 of a feed bar 33. The feed bar 30 may have a threaded shank portion 35 for engagement within a feed nut 36 journaled against axial motion in a suitable portion of the machine bed and the bar 33 may have a threaded extension 37 engaging in a nut 38 similarly held against axial motion. Suitable means may be provided for turning these nuts 36 and 38 as desired to move their respective feed bars axially. Thus the nut 36 may have keyed thereto a hand wheel 40 provided with handles 41 thereon and for automatic feed it may have a ratchet ring 42 secured thereto for engagement by a feed ratchet which may, if desired, be carried by a reciprocating bar 43 (Fig-

45 50 55

ure 1) actuated from within a casing 44. A member 400 which may be rotated with the wheel 40 or latched in stationary position may be provided with a micrometer feed pinion having an actuating handle 401 and it may extend over the ring 42 and act as a power feed limit stop when the member 400 is unlatched. The nut 38 may have secured thereto a gear 45 which may be connected through an idler gear 46 with a gear 47 on a feed shaft 48. This shaft 48 may be provided with a hand wheel 49 similar to the hand wheel 40, and a ratchet mechanism micrometer hand feed, and feed limit stop similar to that applied to the nut 36.

In Figure 5 a modification is shown in which the lower feed abutment at 50 comprises a bar of circular cross section, while the upper abutment 51 is formed as a flat bar. A bar of circular cross section permits angular adjustment when worn to present a fresh guide surface. The flat bar 51 may be found more convenient when there is considerable irregularity of contour. Either may be formed readily by a turning operation. For internal combustion engine cylinders of the type where the cylindrical barrel is secured to the head by a threaded connection, as illustrated in Figure 3, the barrel being shown at 55 and the head at 56, in order to allow for expansion under normal working conditions of heat, it is found desirable to slightly enlarge the bore of the barrel inwardly from its head end and to have a reduced internal diameter at the extreme end. It is also found desirable to form the open end of the cylinder as at 57 with a slightly decreased internal diameter. These decreases from the diameter of the intermediate portion of the cylinder length produce slight fillets at the ends. While these departures from true cylindrical contour are only a few thousandths of an inch, they are found to be highly desirable but in order that they may be indicated on the drawings, these variations are shown very much exaggerated.

In grinding the inner wall of the barrel of the cylinder with the machine shown in Figures 1 and 4, the barrel is supported in a suitable fixture 60 (Figure 2) by which it may be clamped in position with respect to the work holder 2, and the grinding wheel 7 is caused to traverse it. Because of the very slight variation from true cylindrical contour desired in the finished barrel, this invention provides for rough grinding the interior to cylindrical contour and then producing the slight departures from cylindrical contour at or adjacent to the ends of the barrel in the finish grinding, and preferably with the grinding wheel contour slightly modified from the cylindrical contour desirable for best results during the rough grinding.

A wheel truing diamond is illustrated at 65, this being positioned beyond the outer end of the work so that the wheel may be trued in an extended portion of its traverse where it is clear from the work and in what may be termed the truing range of the wheel traverse as distinguished from the working range during which the wheel is in contact with the work. Assuming that the work is placed in the work holder for the rough grinding operation, the grinding wheel 7, preferably trued to cylindrical contour, is caused to traverse the cylinder, the position of the wheel with respect to the wall of the work being adjusted as desired through that one of the feed mechanisms which is provided with the abutment arranged for producing a straight line traverse.

The wheel is fed into the work to the extent desired for the rough grinding operation by a suitable operation of the selected feed mechanism. For example, the machine may be equipped to operate as shown in my Patent No. 2,176,985 previously mentioned. If desired, the wheel may be trued cylindrical as often as desirable to preserve cylindrical contour and a good grinding face, through an extended traverse of the wheel, the traverse being linear and in line with the traverse within the work, the diamond 65 being moved into position for the truing operation in any suitable manner.

After the rough grinding has been completed, the feed mechanism for the rough grinding is retracted and the feed mechanism for finish grinding brought into operation. It will be assumed that this finish grinding feed mechanism is that employing the abutment 20 of circular cross section, although as before stated, it might be the flat bar abutment if desired. The finish abutment, however, is not the same diameter throughout, but may be formed as shown in Figures 6, 7 and 8 with a cylindrical intermediate portion 70, a tapered portion 71, and a smaller diameter cylindrical portion 72 adjacent thereto toward one end of the abutment. At the other side of the cylindrical portion 70 is an enlarged diameter portion 73 formed by a pair of tapered walls 74 and 75. Beyond this portion 73 is a smaller diameter portion 76 between tapered portions 77 and 78.

The wheel being retracted from the work into the position shown in Figure 8, and the feed mechanism including the follower roll 31 being in contact with the bar 20 at the position shown in Figure 8, an outward traverse of the wheel carrier will bring the smaller diameter portion 76 to the follower and as the traverse away from the work continues, the grinding wheel will be trued to the contour shown in Figures 6, 7 and 8, having a central large diameter portion 80 and tapered to a smaller diameter at opposite ends as at 81. The wheel being thus trued, traverse of the work is again commenced. Preferably the wheel is moved into the work and then fed thereagainst in the position of Figure 7 and traversed with a short stroke, as by hand control, until the wheel has been fed in sufficiently to engage the portion 85 on a more extended traverse, at which time the normal power grinding traverse of full length is started and the finish grinding completed with the full traverse. The intermediate portion 85 is cylindrical and a reduced sloping portion 86 is ground adjacent to the open end of the barrel. Near to the opposite end of the barrel, there is ground an enlarged diameter portion 83 and at the end an inwardly sloping portion 84. The follower roll 31 engages the enlarged diameter portion 73 of the abutment when working on the end of the cylinder barrel adjacent to the head and engages the portion 71 to form the taper contour adjacent to the open end of the cylinder. Thus the finish grinding operation produces the cylinder with its main portion truly cylindrical and its end portions having the slightly different but desired contours for the completed cylinder.

In Figures 9 and 10 is shown a modification in which the cylindrical rough grinding and modified finish grinding contours may be produced with a single grinding wheel feed mechanism. In this case a pair of truing devices 90 and 91 are employed, one of these for truing the wheel to cylindrical contour, and the other for truing it to a convex contour. The abutment 93 which

determines the angular position of the wheel carrier, and thus the feed position of the wheel with relation to the work, is provided with a cylindrical contour for the greater portion of its length. A portion of this cylindrical contour length as from *a* to *b* corresponds to the grinding traverse of the work. Another portion of this cylindrical contour from *a* to *c* is for an extended traverse during which the truing device *98* when moved into operative position may true the wheel to cylindrical contour, this being the contour of the abutment between the portions *a* and *c*. This is the position shown in Figure 9. This abutment *93* has another portion between the points *d* and *e* which is of decreased diameter. When the grinding wheel traverse is extended so that the follower *31* engages this portion of the bar *93*, the wheel is so guided past the truing device *91*, which may be brought in operative relation to the grinding wheel, to true the grinding wheel to the convex contour illustrated in Figure 10 for the finish grinding operation. When the wheel of this contour is then applied for the finish grinding and the wheel traverse is limited to the distance *a*-*b* so that the wheel does not clear the work at either end, the resultant contour is that shown in Figure 11, where there is an intermediate central portion of true cylindrical contour and tapered end portions at *95* and *96*. The feed will then be retracted before the traverse is extended to remove the wheel from the work, so that the finished wheel contour remains as shown in Figure 11. While this contour is not as desirable as that shown in Figures 2, 3, 6, 7 and 8, it may in some cases serve the desired purpose. While as shown, the departures from cylindrical contour taper are in substantially straight lines, and the grinding wheel for finish grinding is similarly arranged, this is not essential as the changes of contour may be along curved instead of straight lines if desired.

It will be noted that the various contours may be made on the same piece of work with a single chucking of the work so that these various contours are produced in definite accurate relation one to the other.

It should be evident to those skilled in the art that various other changes and modifications might be made without departing from the spirit or scope of this invention as defined by the appended claims.

I claim:

1. A grinding machine having a work support, a grinding wheel shaft for supporting a grinding wheel, means for relatively reciprocating said wheel shaft and work support to cause a grinding wheel on said shaft to traverse work on said support, a plurality of mechanisms for producing and controlling relative feed motions of said shaft and support, each of said controlling mechanisms including a templet for controlling said feed motions automatically in accordance with the relative traverse positions of said wheel and the work and the contour of the controlling template, said templates having different controlling contours, and means for selectively presenting one or another mechanism in operative feed and controlling position whereby each of said mechanisms may be rendered effective for the same work piece with a single chucking of said work piece.

2. A grinding machine having a work support, a grinding wheel shaft for supporting a grinding wheel, means for reciprocating said wheel shaft to traverse a grinding wheel carried by said shaft along work on said support, a plurality of mech-

anisms for producing and controlling a feed motion of said shaft, each of said controlling mechanisms including a template for controlling such feed motions automatically in accordance with the traverse positions of said wheel and the contour of the controlling template, said templates having different controlling contours, and means for selectively presenting one or another of said mechanisms in feed and controlling operative positions whereby each of said mechanisms may be rendered effective for the same work piece with a single chucking of said work piece.

3. In combination, means for supporting tubular work, a grinding wheel, two wheel truing devices, means for effecting a relative traverse of said wheel axially of the work to cause said wheel to grind the inside of said work, means for controlling one of said truing devices at one time during an extended portion of such traverse to true said wheel to cylindrical contour, means for controlling the other of said truing devices and wheel at another time during such extended traverse portion to true said wheel to a convex contour, means for controlling the path of grinding traverse while said wheel is of cylindrical contour to effect a roughing cylindrical grinding cut, and means for controlling the path of grinding traverse while said wheel is of convex contour to effect a finishing grinding cut departing from cylindrical at a portion of the work and while the work remains in the same relation to said work supporting means as during the roughing cut.

4. In a grinding machine having a rotary work support, an axially movable wheel support rockable about an axis spaced from the axis of rotation of work on said work support, a grinding wheel carried by said support, means for reciprocating said wheel support axially to cause said wheel to traverse work carried by said work support, a pair of means selectively operable to control the angular position of said wheel support as said wheel support is reciprocated, the means of said pair being set for different controls, and a wheel truing device, and a means corresponding to each of said pair of means for causing said truing device to true the wheel to a contour, each different from the other and corresponding to such selection, whereby the work may be ground first to one contour by the wheel trued to one contour and then to a different contour by the wheel trued to a different contour while the work remains in the same relationship to said work supporting means.

5. In a grinding machine having a rotary work support, an axially movable wheel support rockable about an axis spaced from the axis of rotation of work on said work support, a grinding wheel carried by said support, means for reciprocating said wheel support axially to cause said wheel to traverse work carried by said work support, means for controlling the angular position of said wheel support in different portions of its axial motion, and a plurality of wheel truing devices positioned at longitudinally spaced points adjacent to the path of motion of said grinding wheel, said position controlling means being differently contoured in lengthwise portions corresponding to the positions of said truing devices to true said wheel to different contours, whereby said wheel trued to different contours may be operative on the same work piece at different times and with a single chucking of the work in said work support.

6. A grinding machine having members com-

prising a carrier for a rotary work support and a grinding wheel carriage mounted for relative motion transverse to the axis of rotation of said work support, means for relatively reciprocating said holder and wheel carriage substantially parallel to said axis, a plurality of templates carried by one of said members and a follower for each template carried by the other of said members for traverse of its respective template during such reciprocation and controlling the transverse position of said carriage during such reciprocation, and means for independently adjusting said followers with respect to their respective templates to bring any selected one of said followers into operative relation to its template while the others are inoperative, whereby a work piece may be subjected to grinding operations controlled by a plurality of said templates during a single chucking.

7. A grinding machine having members comprising a holder for a rotary work support and a grinding wheel carriage mounted for relative motion transverse to the axis of rotation of said work support, a grinding wheel mounted on said carriage, means for reciprocating said holder substantially parallel to said axis throughout a grinding traverse and an extended wheel truing traverse, a wheel truing device positioned to true the wheel during said extended wheel truing traverse, a plurality of templates carried by one of said members and a follower for each template carried by the other of said members for traverse of its respective template during such reciprocation and controlling the transverse position of said carriage during such reciprocation, each of said templates having a portion with which its follower cooperates during work grinding and a portion with which its follower cooperates during wheel truing, and means for independently adjusting said followers with respect to their respective templates to bring any one selected follower into operative relation to its template while the others are inoperative, whereby a work piece may be subjected to grinding operations controlled by a plurality of said templates during a single chucking.

8. In a grinding machine, a bed, a rotary work support carried by said bed, an arm mounted on said bed for pivotal and axial motion with respect to the pivotal axis, a grinding wheel carried by said arm for traversing work carried by said work support on axial motion of said arm and for feeding and retracting motions on swinging of said arm, a plurality of pairs of cooperating members, one member of each pair being a template and the other of said members being a follower for traversing said template, one of the members of each pair being carried by said arm and the other of said members being carried by said bed, and means for adjusting the bed-carried member of each pair into and out of cooperative relation to its cooperating member, whereby any selected one of said pairs of members may be made effective to control the angular position of said arm in accordance with the axial position thereof as determined by the contour of its respective template and a plurality of said pairs of members may be sequentially effective on a work piece during a single chucking of a work piece.

9. In a grinding machine, a bed, a rotary work support carried by said bed, an arm mounted on said bed for pivotal and axial motion with respect to the pivotal axis, a grinding wheel carried by said arm for traversing work carried by said work support on axial motion of said arm

and for feeding and retracting motions on swinging of said arm, a plurality of pairs of cooperating members, one member of each pair being a template and the other of said members being a follower for traversing said template, one of the members of each pair being carried by said arm and the other of said members being carried by said bed, said arm-carrying members being located at different distances from said arm axis, and means for adjusting the bed-carried member of each pair into and out of cooperative relation to its cooperating member, whereby any selected one of said pairs of members may be made effective to control the angular position of said arm in accordance with the axial position thereof as determined by the contour of its respective template and a plurality of said pairs of members may be sequentially effective on a work piece during a single chucking of a work piece.

10. In combination, means for supporting work, a grinding wheel, means for effecting a traverse of said wheel relative to work carried by said work holder within a working range and outside of said working range in a wheel truing range, a plurality of wheel truing tools located at different axial portions of said truing range, means including templates and followers for traversing said templates as the wheel traverses, determining the position of said wheel transverse to its traverse during such traverse, and means for rendering any selected one of said truing tools operative to true the wheel to a contour determined by the contour of the portion of the template controlling the transverse position of said wheel in that portion of the truing range within which the selected truing tool is positioned, whereby a work piece may be subjected to grinding operations controlled by a plurality of said templates during a single chucking.

11. In combination, means for supporting work, a grinding wheel carriage, means for rotarily supporting a grinding wheel on said carriage at a selected axial position, means for effecting a traverse of said carriage relative to said work support within a working range wherein said wheel may operate on work carried by said supporting means and beyond said working range in one direction in a wheel truing range, a plurality of wheel truing devices located at different axial portions of said truing range, means including a template and a follower for traversing said template as the carriage traverses for controlling the transverse position of said carriage, and means for rendering any selected one of said devices operative to true the wheel to a contour determined by the contour of the portion of the template controlling the transverse position of the carriage in that portion of the truing range during which the grinding wheel is in effective axial relation to the selected truing device, whereby a work piece may be subjected to grinding operations controlled by a plurality of said templates during a single chucking.

12. In combination, means for supporting tubular work, grinding mechanism including an internal grinding wheel, wheel truing means positioned to act on said grinding wheel when said grinding means is retracted axially relative to the work, means for producing relative motion of said work and wheel axially, and a plurality of mechanisms selectively operable to control the position of said wheel transverse to the work axis, each of the controlling means including a former cam and a follower for traversing its respective former cam, each of said former cams having a

lengthwise portion for controlling the position of said wheel while in grinding relation to the work, and a lengthwise portion for controlling the position of said wheel while said wheel is in operative relation to truing means, said portions of one of said former cams being contoured to produce cylindrical grinding of the work and cylindrical

truing of said wheel, and the portions of the other of said former cams being contoured one to grind the work in at least a portion of its length tapered, and the other portion being contoured to cause truing of said wheel to convex contour.

MERTON H. ARMS.
